WHEEL COVER FOR AN AUTOMOBILE

George A. Schmidt, Detroit, Mich., assignor to Chrysler Corporation, Highland Park, Mich., a corporation of Delaware

Application July 26, 1955, Serial No. 37,127

Term of patent 7 years

(Cl. D14—30)

Fig. 1 is a front elevational view of a wheel cover for an automobile, showing my new design;

Fig. 2 is a sectional view taken on line 2—2 of Fig. 1;
Fig. 3 is a fragmentary perspective view thereof; and Figs. 4 and 5 are sectional views taken on lines 4—4 and 5—5, respectively, of Fig. 1.

The dominant feature of my design resides in the full line portion of the drawing.

I claim:

The ornamental design for a wheel cover for an automobile, substantially as shown and described.
